DRAINAGE TRAY FOR SINK OR THE LIKE

Norman Gardner, New Rochelle, N.Y., assignor to Joy Plastics, Inc., New York, N.Y., a corporation of New York

Filed Sept. 20, 1965, Ser. No. 87,079

Term of patent 14 years

(Cl. D9—6)

FIG. 1.

FIG. 2.

FIG. 3.

FIG. 4.

FIGURE 1 is a top view in perspective of a drainage tray for sink or the like, showing my new design.

FIG. 2 is a bottom plan view thereof.

FIG. 3 is a side elevational view thereof. The side not shown has substantially the same appearance as the side shown.

FIG. 4 is an end elevation view thereof.

I claim:

The ornamental design for a drainage tray for sink or the like, as shown and described.
